(57) **CLAIM**

The ornamental design for a waterproof cover for wireless headset, as shown and described.

DESCRIPTION

FIG. 1 is a first perspective view of an embodiment of a waterproof cover for wireless headset, showing my design; FIG. 2 is a second perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is a perspective view of thereof in an environment in which it may be used.

The broken lines in the drawings depict unclaimed portions of the waterproof cover for wireless headset and form no part of the claimed design.
